UNITED STATES PATENT OFFICE.

FRED S. CARR, OF NEWTON, MASSACHUSETTS, ASSIGNOR TO CARR FASTENER COMPANY, OF CAMBRIDGE, MASSACHUSETTS, A CORPORATION OF MAINE.

SEPARABLE FASTENER.

1,387,108.

Specification of Letters Patent.

Patented Aug. 9, 1921.

Application filed January 16, 1920. Serial No. 351,774.

To all whom it may concern:

Be it known that I, FRED S. CARR, a citizen of the United States, and a resident of Newton, in the county of Middlesex, Commonwealth of Massachusetts, have invented an Improvement in Separable Fasteners, of which the following description, in connection with the accompanying drawings, is a specification, like characters on the drawings representing like parts.

This invention pertains to improvements in separable fasteners, and more particularly, though not exclusively, to separable fasteners for use in securing automobile curtains and the like. One of the purposes of the invention is to provide a fastener of simple construction having great holding power, in which the stud and socket can be readily separated without complex manipulation.

In the drawings, which show a preferred construction of one illustrative embodiment of my invention:—

Figure 1 is a front elevation of a portion 25 of a curtain having a preferred form of fastener secured thereto;

Fig. 2 is a section, partly in elevation, on the line 2—2 of Fig. 1;

Fig. 3 is a rear view of a socket member 30 taken from the back of a curtain;

Fig. 4 is a section on the line 4—4 of Fig. 2; and

Fig. 5 is a side elevation of the attaching part of the socket member prior to assembly.

Referring to the drawings and to the preferred form of my invention selected for illustrative purposes, I have shown a fastener including a resilient stud having a head 5, a neck 6 and a secondary neck 7, 35 said stud being rendered resilient preferably in the manner shown in my copending application filed herewith, Serial No. 351,773, being slit longitudinally, the slots preferably extending into the base of the stud as 40 shown in said application. The preferred form of stud preferably cooperates with a socket, which may be and preferably is comprised of two parts, including a socket part 8 providing a stud-receiving aperture and 45 preferably having at one side thereof a rearwardly extending lip 9 which is preferably curved in cross-section to embrace a portion of the stud, preferably approximately one-half, as best shown in Fig. 3, and which

preferably provides a jaw part 10 for engagement with the secondary neck 7 of the stud. The preferred form of socket also preferably includes means for turning, 55 clenching and engaging any suitable prongs 11 which preferably project rearwardly 60 from a socket-securing plate 12 located on the opposite side of the socket-carrying fabric 13 from the socket 8. The before described securing construction, providing 65 prong-turning and engaging parts in a single piece, is of use in many connections, but is particularly useful in connection with the securing of sockets, especially sockets of the three-side lock type herein described. By this 70 construction the number of parts used is reduced to a minimum and the ends of the securing prongs are concealed. It is obvious that for some purposes the concealing of the ends of the prongs is not essential and that this feature of my invention may be 75 dispensed with while availing of other advantages thereof.

The aperture in the socket for receiving the stud is preferably annular and slightly smaller than the major diameter of the 80 head of the stud, so that when the stud is to be entered in the socket, the resilient portions of the stud may spring together to reduce the effective diameter of the head, the resiliency being such that when the parts 85 have reached the position shown in Fig. 2, the stud will expand, preferably providing, however, some slight compression of the stud so that the parts will not rattle. That portion of the stud adjacent the neck 6 will have 90 greater capacity for resilient movement than that portion of the stud adjacent the secondary neck 7, because the secondary neck 7 is nearer the base of resiliency than the neck 6. The shoulder between the neck 6 of 95 the stud and the head 5 thereof is preferably somewhat sloping, as shown. When the socket is tipped relative to the stud in the direction indicated by the arrow in Fig. 2, the head of the stud will be compressed 100 somewhat and the socket will tip about that portion of the margin of the aperture which is directly above the stud and which engages the neck 6. The jaw 10 will, therefore, be withdrawn from the secondary neck 7, and as the stud is tipped further, the head of the 105 stud will be readily withdrawn from the stud-receiving aperture. Separation of stud

and socket by relative rectilinear movement is prevented by the jaw 10 engaging the secondary neck 7 because the stud has not sufficient resiliency adjacent the neck 7 to permit the jaw 10 to clear the projection in front of the neck 7 except by the tipping movement before described. Relative tipping movement of stud and socket in any direction except that indicated by the arrow in 10 Fig. 2 is precluded by reason of the fact that the lip or flange 9 extends around the sides of the stud. The jaw 10 preferably engages a somewhat smaller proportion of the circumference of the stud than does the lip 9, so that 15 during the stud and socket disengaging tipping movement, the lip 10 will exert little, if any, compressive force against the sides of the stud adjacent the secondary neck 7.

It will be understood that I use the word 20 "fabric" in its broader sense to include not only woven materials, but any flexible carrying medium.

While I have shown and described a preferred form of one embodiment of my invention, it will be understood that changes 25 involving omission, substitution, alteration and reversal of parts, and even changes in the mode of operation, may be made without departing from the scope of my invention, 30 which is best defined in the following claims.

Claims:

1. An element for separable fasteners comprising, in combination, a pronged member for attachment to one side of a flexible carrier and a single part for attachment to the opposite side of the flexible carrier, said integral part providing integral anvil portions for turning the prongs of the pronged member and integral holding portions engaging the turned prongs.
2. An element for separable fasteners comprising, in combination, a pronged member for attachment to one side of a flexible carrier and a single part for attachment to the opposite side of the flexible carrier, said integral part providing integral anvil portions for turning inwardly the prongs of the pronged member and integral holding portions engaging the turned prongs.
3. A socket for separable fasteners and means for securing the same to a flexible carrier comprising, in combination, a front part having rearwardly projecting prongs, said part for attachment to one side of the flexible carrier with the prongs projecting therethrough, and supplemental means for attachment to the other side of the flexible carrier, said supplemental part having a stud-receiving aperture therein and providing means for turning said prongs and

for holding said front part and supplemental part together.

4. A socket for separable fasteners and means for securing the same to a flexible carrier comprising, in combination, a front part 65 having rearwardly projecting prongs, said part for attachment to one side of the flexible carrier with the prongs projecting therethrough, and supplemental means for attachment to the other side of the flexible carrier, said supplemental part having a stud-receiving aperture therein and providing means for turning said prongs and for holding said front part and supplemental part together with said prongs clenched and 70 concealed within the supplemental part.

5. A socket for separable fasteners comprising, in combination, a plate having an opening therethrough for the reception of the head of a stud, said plate providing boss 80 means for turning prongs, and having flanged portions with apertures through which the prongs may pass adjacent said boss means.

6. A socket for separable fasteners comprising, in combination, a plate having an opening therethrough for the reception of the head of a stud, said plate providing boss means for turning prongs, and having flanged portions with apertures through 90 which the prongs may pass adjacent said boss means, said plate also providing a rearwardly projecting lip for engagement with the shank of the coöperating stud.

7. A socket for separable fasteners comprising, in combination, a plate having an opening therethrough for the reception of the head of a stud, said plate providing boss means for turning prongs, and having flanged portions with apertures through 95 which the prongs may pass adjacent said boss means, said plate also providing a rearwardly projecting lip for engagement with the shank of the coöperating stud, said lip having jaw means projecting therefrom a substantial distance rearwardly of said opening.

8. A three-side lock fastener comprising, in combination, a resilient stud and a rigid socket, said socket comprising two pieces 110 only, the one a socket proper for engaging the stud on that side of the flexible socket-carrying fabric from which the stud enters, and the other a prong-carrying part having prongs for projecting through the carrying fabric and clenching within the socket proper.

In testimony whereof, I have signed my name to this specification.

FRED S. CARR.
